UNITED STATES PATENT OFFICE.

EDWARD EUGENE RIORDAN, OF LIMA, OHIO.

COMBINED VACUUM CLEANER AND DISINFECTOR.

Application filed July 31, 1923. Serial No. 578,777.

To all whom it may concern:

Be it known that I, EDWARD EUGENE RIORDAN, a citizen of the United States, and a resident of Lima, in the county of Allen and State of Ohio, have invented a new and useful Improvement in Combined Vacuum Cleaners and Disinfectors, of which the following is a full, clear, and exact description.

My invention relates to improvements in combined vacuum cleaners and disinfectors, and it consists in the combinations, constructions, and arrangements herein described and claimed.

An object of my invention is to provide a disinfecter which may be readily secured to an ordinary vacuum cleaner, whereby the vacuum cleaner is also adapted to disinfect the room as it cleans the same.

A further object of my invention is to provide a device of the character described which has novel means for disinfecting the carpet of the room.

A further object of my invention is to provide a device of the character described in which the strength of the disinfecter may be varied at will.

A further object of my invention is to provide a device of the character described in which the disinfected air is forced into the fiber of the carpet or rug, thereby thoroughly disinfecting the same.

A further object of my invention is to provide a device of the character described which is simple in construction and which is durable and efficient for the purpose intended.

Other objects and advantages will appear in the following specification, and the novel features of the invention will be particularly pointed out in the appended claims.

My invention is illustrated in the accompanying drawing, forming part of this application, in which—

Figure 1 is a side elevation of the device as shown operatively applied to a vacuum cleaner, portions of the device being broken away,

Figure 2 is a plan view of the device,

Figure 3 is a sectional view of the disinfecter,

Figure 5 is a modified form of the device, and

Figure 4 is a diagrammatic view of the

device shown operatively connected to a closet.

In carrying out my invention, I make use of an ordinary vacuum cleaner which is shown diagrammatically in Figure 1 and which comprises a suction mouth 1, a fan 60 actuating motor 2, a guiding handle 3, and a dust bag 4. The suction mouth 1 has an intake opening 5 which is in communication with the fan of the motor (not shown) and also in communication with an outlet pipe 6. 65 The bag 2 is connected to the pipe 6 by a coupling 7. The parts heretofore described are ordinary in construction and form no part of my invention except in so far as they cooperate with the parts about to be 70 described. I have only mentioned and shown the parts which need be named in describing the operation of the device.

I then provide a liquid container 8 which is adapted to hold a disinfectant such as 75 formaldehyde 9 therein. The container 8 is provided with a cover 10 which closes the inlet opening of the container. A valve 11 controls the amount of fluid passing through the outlet of the container and is regulated 80 by a handle 12, whereby the amount of liquid passing from the container is varied at will. A heating pan 13 is disposed beneath the valve 11 and is adapted to receive the disinfectant as it drops therein. This 85 heating pan has resistance wires, indicated generally at 14, disposed therein, these wires being in electrical connection with the source of current. It is obvious that when the motor 2 is started, the current will also flow 90 through the wires 14 and heat the pan 13, thereby evaporating the liquid which drops from the casing 8. In this manner the air surrounding the pan 13 is thoroughly disinfected. The disinfecting attachment is also 95 shown diagrammatically. It is obvious that it may be secured to the sweeper by any means. The special construction of the disinfecter and the attaching means, may be changed for different types of standard 100 sweepers without departing from the spirit and scope of my invention. The invention is to utilize the air escaping from the dust bag, for disinfecting the surface over which the sweeper is moved.

The air which escapes from the bag 4 is conveyed back over the pan 13 and out into the fiber of the carpet or rug which the

sweeper is cleaning by a novel means. This means comprises a bag 15 which encloses the bag 4. A pipe 16 connects the bag 15 with the compartment 17. The compartment 17 is expelled directly above the carpet and is forced through the fiber by the intake of the pipe 5. It is obvious therefore that the device provides an efficient means for disinfecting the floors of sick rooms or the like. 70 The device also cleans the floor as it disinfects, thus performing a two-fold function. The device is simple in construction and can be readily attached to any ordinary vacuum cleaner. It is obvious that any 75 modifications and adaptations of the form of the device pictured in the accompanying drawings may be provided without departing from the spirit and scope of my invention as disclosed in the foregoing specification and set forth more particularly in the appended claims.

From the foregoing description of the various parts of the device, the operation 15 thereof may be readily understood. The casting 8, together with the pipe 18 and the pipe 16, is disposed upon the suction head 1 and is secured thereto by any means (not shown). The bag 15 is disposed around the bag 4 and 20 is placed in communication with the compartment 17 by connecting it to the pipe 16. The vacuum cleaner is now operated in the ordinary manner and draws the air through the pipe 5 and forces it into the bag 4. The 25 bag 4 retains the greater portion of the dust which is in the air, but it is obvious that some of the dust will escape with the air as it passes out of the bag 4. The bag 15 prevents the air from passing there- 30 through and causes the air to flow through the pipe 16 and into the compartment 17. The valve 11 has previously been regulated so as to determine the amount of disinfectant flowing into the pan 13 so as to provide 35 the proper amount of disinfectant to the air as it passes from the pipe 16, through the compartment 17, and into the pipe 18. The small amount of dust in the air is also de- 40 posited and it will therefore be apparent that the air flowing out through the pipe 18 is entirely cleaned and is thoroughly disinfect. The openings of the pipes 5 and 18 are adjacent to one another and are dis- 45 posed directly above the carpet or floor 19. A great portion of the air sucked into the pipe 5 is drawn directly from the air that is expelled from the pipe 18. This air in 50 passing from the pipe 18 to the pipe 5 is forced through the fiber of the carpet or the rug and thoroughly disinfects the same. In this manner, the carpet or rug is effect- 55 ally disinfected.

In disinfecting a room with the ordinary means, it is practically impossible to also 55 disinfect the carpet. This is due to the fact that cold air currents are constantly moving across the floor and thus prevent the disinfectant from coming into contact with the floor. In most cases, the disin- 60 fectant comes within about two or three inches of the floor and cannot penetrate any further. The carpet is one of the most necessary things to disinfect in a sick room. With my present device, this is readily and 65 easily accomplished, since the disinfected air

In Figure 5 I have shown a slightly modified form of the device in which the ordinary dust retaining bag 4 is done away with and the air which is exhausted from the suction head 1 is conveyed directly to the disinfecting compartment. This form of the device is identical with the form here- 80 tofore disclosed, except for the above mentioned differences. Similar parts will there- 85 fore be provided with like numerals and will need no further explanation. A pipe 20 communicates with the intake pipe 5 and with the compartment 17. In the for- 90 mer form of the device, the pipe 6 was sub- 95 stituted for the pipe 20 and was in com- 100 munication with the bag 4. By placing the compartment 17 in direct communication with the intake pipe 5, all of the air is 105 conveyed directly to the compartment 17. In this case all of the dust in the air is de- 110 posited in the compartment 17 and the pure and disinfected air is expelled through the pipe 18. The same operation takes 115 place as disclosed in the preferred form of the device, and the device will therefore effec- 120 tually disinfect the floor of a room. By dis- 125 posing the disinfector on the vacuum cleaner, I provide a device which is port- 130 able and which may therefore be readily conveyed from room to room to disinfect the floors of the latter. The device is ex- 135 ceedingly simple in construction and per- 140 forms a useful function.

The pipes 16 and 20 are preferably pro- 145 vided with a valve which controls the amount of air passing into the compartment 17, and expels the excess air into the room. In the drawings I have shown such a valve 21 as being disposed in the pipe 16. The switch 22 controls the electricity passing through the wires 14. It is obvious that the switch 22 may be opened, thus permitting the liquid 9 flowing from the valve 11 to 150 evaporate without being aided by the heated pan 13.

In Figure 4, I have shown a diagram- 155 atic view of the device when used to disinfect a closet 23 or the like. An inlet pipe 160

24 communicates with the top of the closet and with the device, while an exhaust pipe 25 communicates with the bottom of the closet and with the device. In this manner, 5 the air within the closet is thoroughly disinfected.

I claim:

1. The combination with a vacuum cleaner having a suction nozzle, and a dust bag, of 10 a bag disposed around said dust bag, a disinfecting chamber carried by said cleaner and in communication with said second named bag, and a pipe leading from said chamber and terminating adjacent to the 15 intake nozzle whereby the disinfected air is brought into contact with the supporting surface.

2. The combination with a vacuum cleaner having a suction nozzle, of a disinfecting 20 chamber in communication with said nozzle, a reservoir adapted to carry a liquid disinfectant, a heating pan under said reservoir adapted to change the liquid into a vapor, a

valve for said reservoir controlling the amount of liquid passing into the pan, and 25 a pipe leading from said chamber and terminating adjacent to the intake nozzle.

3. The combination with a vacuum cleaner having a suction nozzle and dust bag, of a disinfecting chamber carried by said cleaner, said disinfecting chamber comprising a bag inclosing said first named bag and adapted to receive all of the air that passes through said first named bag, a disinfecting chamber communicating with said second named bag, a 30 heating pan disposed in said chamber, a reservoir disposed above said pan, a valve controlling the flow of a disinfecting liquid from the reservoir to the pan, a second nozzle in communication with said chamber and 35 terminating adjacent to said first named nozzle whereby the suction in said first named nozzle will draw the air passing out through said second named nozzle. 40

EDWARD EUGENE RIORDAN.
